Attorneys.

UNITED STATES PATENT OFFICE.

WILLIAM S. CROUCH, OF TACOMA, WASHINGTON, ASSIGNOR TO LINE CARRYING BUOY COMPANY, A CORPORATION OF DELAWARE.

BUOY.

1,339,321.

Specification of Letters Patent.

Patented May 4, 1920.

Application filed September 3, 1919. Serial No. 321,355.

To all whom it may concern:

Be it known that I, WILLIAM S. CROUCH, a citizen of the United States, residing at Tacoma, in the county of Pierce and State 5 of Washington, have invented certain new and useful Improvements in Buoys; and I do hereby declare the following to be a full, clear, and exact description of the invention, such as will enable others, skilled in the art 10 to which it appertains to make and use the same.

This invention relates to buoys and particularly to that form of device designed to carry cord or cable and valuables, and provided with a means for permitting said cable 15 to be paid out according to the movement of the buoy.

An object of this invention is to provide an improved buoy for sending a line from one vessel to another, and from a vessel to a man overboard, and from a vessel to shore, and from the shore to a vessel, and for indicating the position of an anchor, and for carrying valuables, and for providing a 20 suitable floating body for carrying a supply of cable designed to have its free end secured at a point from which the body starts and to be paid out as the body moves with the wind upon the water.

30 A further object of this invention is to provide an improved means of forming a sealed joint of the cap for said buoy.

A further object of this invention is to improve means for locking said buoy and 35 to provide a direct instead of an angular pull upon the thin metallic parts of said buoy and to provide a positive means for holding the said cap in a locked relation by said locking means against yielding of the 40 thin metallic parts of said cap and said buoy.

A further object of this invention is to provide and simplify the structure of the locking means for said cap and of said buoy 45 and to unify this structure with the means for holding a cable carrying float in said buoy.

A further object of this invention is to provide a means within said buoy for receiving, carrying and protecting moneys, 50 jewelry, papers and other valuables.

A further object of this invention is to

provide an improved means for locking and inserting a reel within said buoy.

A further object of this invention is to provide a means for reducing a counterbalancing lead weight forming a keel for said buoy and to lower the said weight and change the gravity of said buoy to enable the use of a lesser amount of lead or other counterbalancing material and further to extend the said buoy downward in order to form an anchor when the said buoy strikes shallow water and at the same time make the said extension collapsible for the purpose of simplifying transportation, handling, storage and stowage of the said buoy.

A further object of this invention is to provide a means for supporting a basket for carrying said valuables and to make the said means common with the means for locking and inserting the said reel.

With these and other objects in view the invention consists of the construction, combination and in the detail and arrangement 75 of parts as hereinafter more fully described and claimed.

In the drawings:

Figure 1 is a central vertical section partly in elevation of the buoy.

Fig. 2 is a top plan view of the buoy.

Fig. 3 is a top plan view of the buoy with the cover removed as taken at 3-3 in Fig. 1.

Fig. 4 is a detail perspective of the means 85 for inserting and locking the reel.

Fig. 5 is a top view of Fig. 4.

Fig. 6 is a detail side elevation of the means for locking the cap on the said buoy.

In detail the invention comprises a body 90 casing 1 having therein floats 2 for buoyancy and a reel 3 having a line 4 wound on said reel and extending downward and out through an orifice 5 and having in said line a pin 6. Said casing 1 is cylindrical 95 in formation in its lower part 7 and drawn into a hook formation at 8 and has an extension cylindrical member 9, which is also hooked at 10 so that a portion of 9 telescopes within member 7. At the base of 100 member 9, carrying orifice 5, is a weight 11 of lead or other suitable material having a high specific gravity. Thus, when not in the water, 9 is telescoped within member 7

and substantially inclosed therein, thereby making the space occupied by said buoy normally not beyond the projection of member 7. When in the water, however, member 9 by gravity extends itself outward thus lowering the center of gravity of the said buoy and thereby requiring a lesser weight of the weight 11 to stabilize the said buoy and to keep it in a vertical position and also 10 forming a projection which will tend to strike bottom in shallow water and thereby serve as an anchor in deeper water than if it had not so extended.

Reel 3 is provided with a shaft 12 having 15 a pair of collars 13 adapted to be inserted freely through an orifice 14 in a bracket 15 and to support said reel from lateral motion in a slot 16 of said bracket. When shaft 12 is dropped into said slot 16 a bar 17, 20 having a cleat 18, is inserted through the orifice 14 and held against lateral motion by said cleat, the said bar coming sufficiently near to the said collars to prevent an undesirable upward movement of said 25 shaft when the said bar is affixed to straps 19. Straps 19 span the space between air chamber 2 and also form a support for hooks 20, which said hooks are affixed to a basket 21. Basket 21 is for the purpose 30 of carrying money, jewelry, papers and other valuables, and when inserted is prevented from release by a cap 22 for the said buoy. Cap 22 is held affixed to body 1 by clamps, preferably five in number, consisting of an eye member 23, the said eye 35 member having a pair of eyes, one of said eyes 24 vertical for receiving a bolt member and the other of said eyes 25 lateral for receiving a float cable 26. The bolt 40 member having a bolt 27, having a nut 28 and washer 29, is extended to and flattened at 30 and riveted with three rivets 31. Thus, when the cap is inserted bolt 27 penetrates through the hole 24 and is affixed by 45 nuts and washers 28 and 29. It is obvious therefore that no matter how much the thin metal casing 1 may yield it will be impossible for bolt 27 to be disengaged from eye member 23. It is obvious further that, 50 owing to the arcuate structure of eye member 23 where it is affixed to cap 22, the forces tending to separate the cap 22 and the casing 1 will not be angular upon cap 22 and will not have as great a tendency to dis- 55 tort cap 22 as they would if the said member 23 were affixed upon the side of said cap 22. It is further obvious that the member 23 performs a dual function of forming a lock for affixing the said cap to the said 60 body 1 and also for carrying the said float cable 26. Member 23 is affixed to cap 22 by rivets 33, there being three of said rivets. Thus, if the member 23 were made separate for forming a perforation for receiv-

ing a locking bolt and also with a separate 65 part for holding the said float cable, each of said parts would require at least four rivets, but by the combination of the two said parts, one of said parts normally on the top of said cap 22 and the other of the 70 said parts at the side, the stresses by reason of the reduced angularity are so reduced in this unified structure, that three rivets are all that are essential for holding of the said member. By reason of the further fact 75 that bolt 27 is elongated and normally rests against the casing of body 1 for a considerable length, it is found that three rivets 31 are all that are essential for maintaining 80 this permanent position.

A gasket 34 cylindrically cross sectioned is provided between the cap 22 and the body 1. The purpose of having this gasket cylindrical is to reduce the pressure required for sealing cap 22 in relation to 85 body 1.

What I claim is:

1. A buoy comprising means for buoyancy, a reel for paying out a retaining line, a basket for valuables above said reel, said means for buoyancy surrounding said basket and reel, means for capping said buoy above said basket, and means for holding said basket affixed when said cap is in place and for releasing said basket when said cap 95 is removed.

2. In a buoy, a body member, a cap, a member of relatively heavier metal affixed to said cap, said heavier member provided with an eye to receive a bolt for locking 100 said cap to said body and also an eye to carry a float cable.

3. In a buoy, in combination, air chambers for buoyancy, a body casing surrounding said chambers and formed at its lower 105 end into a tube and a tubular member carrying a weight telescoping with said extended tube.

4. In a buoy, in combination, air chambers for buoyancy, a body casing surrounding 110 said chambers and formed at its lower end into a tube and a tubular member carrying a weight telescoping with said extended tube, and means for arresting the downward movement of said tube carrying 115 said weight.

5. In a buoy, in combination, air chambers for buoyancy, a body casing surrounding 120 said chambers and formed at its lower end into a tube and a tubular member carrying a weight telescoping with said extended tube, and means for arresting the downward movement of said tube carrying said weight, said means including a hook crimp in each of said members.

6. In a buoy, a reel for paying out a line, a shaft for said reel, recesses to freely receive said shaft from the top and means for

locking said shaft from upward movement including a strip slidably mounted above said shaft and means for affixing said strip relative to the body of said buoy.

5 7. In a buoy, in combination, floats for buoyancy, a reel for paying out a retaining line, a receptacle for valuables, a member

affixed to said floats, means for holding said reel in position, said means for holding said reel in position and said receptacle both 10 supported by said member affixed to said floats.

In testimony whereof I affix my signature.

WILLIAM S. CROUCH.
